PIANO ACTION

Filed April 18, 1922

Inventor,
Henry F. Schenuit.
By Hazard & Miller Atty's.

UNITED STATES PATENT OFFICE.

HENRY F. SCHENUIT, OF PASADENA, CALIFORNIA.

PIANO ACTION.

Application filed April 18, 1922. Serial No. 555,105.

To all whom it may concern:

Be it known that I, HENRY F. SCHENUIT, a citizen of the United States, residing at Pasadena, in the county of Los Angeles and State of California, have invented new and useful Improvements in Piano Actions, of which the following is a specification.

My invention relates generally to pianos, and more particularly to a piano action that includes key operated hammers striking downwardly, cushioning devices, damping mechanism and associated parts, the principal object of my invention being to provide a down striking piano action of simplified construction that can be easily and cheaply produced and which is particularly intended for use in pianos of relatively light weight and inexpensive construction.

Further objects of my invention are to provide an improved form of key mounting; to provide simple and efficient means for maintaining the hammers elevated and out of contact with the wires when the keys are held down after being struck, thereby enabling the strings to vibrate freely; to provide improved means for counterbalancing the weight of the forward portions of the keys; and, further, to provide simple and efficient means for actuating the damping devices that serve to normally hold the strings against vibration.

An embodiment of the invention is hereinafter described and is illustrated in the accompanying drawings, in which

Figure 1 is a plan of a group of three keys forming a portion of the keyboard of a piano;

Figure 2 is a vertical section and partial elevation of the action.

More particularly, my present invention relates to that type of piano key actions having a down stroke hammer.

In the illustrated embodiment, the invention is combined with a key 2 which is slotted at 3 from top to bottom to receive a balance pin 4, one end of which is secured as in the pin rail 5. It is understood that the invention is designed to be combined with the several keys of a piano and the action is here shown and described with respect to one key as it is substantially similar in all of the keys.

Preferably the key 2 rests upon a noise deadening support, as a layer or layers of felt or other soft material 6, surrounding

each pin 4 and resting upon the top of the pin rail 5.

Arranged, in the present case, horizontally below the piano keys 2 are the several wires W, one only of which is shown, and which springs from the usual bridge 7 arranged upon the sounding board 8.

Disposed above the wires W and below the keys 2 is a hammer rail 9, and upon this is fulcrumed a series of hammers, of which one is indicated at 10, and consists of an L-shaped arm, the short end of which is provided with the usual striking hammer 11. The longer end of the hammer arm 10 is fulcrumed intermediate its ends upon an individual fulcrum pin 12, in the present case provided in a small bracket 13 fastened to the rear and upwardly and forwardly inclined face 9a of the hammer rail 9. The top face of this rail is shown as slightly recessed behind the fulcrum bracket 13 to provide for the downward swinging of the contiguous end of the hammer arm 10.

It is very desirable to provide means for readily and accurately adjusting the position of the hammer 11 above the respective wire W when the key 2 is in its normal free position and, therefore, at the same time to provide for varying the length of the striking movement of the hammer. To that end the fulcrumed end of the hammer arm 10 is pivotally connected at 14 to the contiguous end of a link 15, and this is shown as inclining upwardly and forwardly slightly from the vertical. It is connected at its upper end by a pivot 16 to the lower end of an adjusting rod 17 which, in turn, is slidably fitted in an aperture 18 provided therefor from the top to bottom of the key 2. This adjusting rod 17 projects both below and above the key and its upper end is designed for attachment to means whereby the position of the rod 17 is not only regulated but also whereby it is firmly locked.

A preferred form of adjusting means for the rod 17 is shown as including a block 20 fastened on the upper end of the rod and being threaded, parallel to the axis of the rod, to receive a jack screw 21 shown as having its lower end provided with a head resting in a seat 22 in the top of the key 2. The head on the lower end of the screw 21 is engaged by means for normally pressing it firmly to its seat 22, and this may consist of a resilient leaf 23 slotted to pass around

the shank of the screw just above its head, while the opposite end of the clamping leaf 23 is supported upon the top of its key and held as by a screw 24.

5 The jack screw 21 is adapted to be engaged by any suitable tool whereby it may be rotated, and thus raise or lower the block 20 and thereby axially shift the rod 18 in its key 2. As here shown, the upper end 10 of the screw 21 is transversely slotted as at 21^a to receive the bit of a screw driver or other suitable implement for rotation of the screw.

From this it will be seen that as the adjusting rod 17 is raised or lowered through its key 2 it will, by means of its connecting link 15, push down or pull up on the connected end of the hammer arm 10 and, therefore, move the hammer toward or from its 20 wire W as is required.

For the purpose of securing and locking the parts in adjusted position, means are provided and, as here shown, include the screw 25 with its head arranged above the 25 block 20 and its shank freely turnable therein, the lower end of the screw 25 being threaded in the key 2 so that after the jack screw 21 has been turned to set the adjusting rod 18 at the desired position thereof 30 the clamping screw 25 is turned so that it will jam down on the block 20, and this will be canted on the jack screw 21 and thereby firmly locked.

Arranged a short distance to the rear of 35 the rails 5 and 9 is a transversely disposed rail 27 in which are seated the usual guide pins such as 28, for the rear ends of the keys 16, and arranged a short distance above this rail 27 and above the rear portions of 40 keys 2 is a transversely disposed rail 29 in which are adjustably seated screws 30. These screws 30 pass upwardly through rail 29. Therefore, their heads are underneath and in order that said screws may be 45 rotated for adjustment from a convenient position above the rail, the upper ends of said screws are provided with diametrically arranged slots 31 that are adapted to receive the end of a screw driver or like adjusting tool. Carried by the rear end of each key 50 and on the top thereof is a cushion 32 that is adapted to contact with the head of the corresponding screw 30 when the key is struck in the usual manner and its rear end elevated. Arranged in the rear portion of 55 the body of each key 2 is a counterbalancing weight 33, preferably a plug or disk or relatively heavy metal, such as lead, and said weight serves to cause the rear ends 60 of the keys to move downwardly after being struck, and the pressure on the forward ends of the keys is relieved. Positioned on rail 27 is a pad or cushion 34 of felt or analogous material, upon which the rear portions of 65 the keys rest when in normal position.

Positioned a substantial distance to the rear of the parts 5 and 9 and disposed above the strings or wires is a transversely disposed rail 35, and pivotally connected to flanges 36, that are seated on said rail, are 70 the rear ends of damper levers 37, there being one arm for each key and string.

Passing vertically through each lever 37 is a screw 38 carrying on its lower end a damper 39 that normally rests on the corresponding string. Positioned on the under side of the free end of each lever 37 is a cushioning pad 40 of felt or analogous material which is adapted to be engaged by the laterally bent lower end 41 of a rod 42 80 that depends from the corresponding key. Under normal conditions this finger 41 occupies a position a short distance below the pad 40. Suitable means is provided for simultaneously raising all of the damper 85 levers, which means preferably includes a rod 43 operated by a usual pedal, the upper end of which rod bears against the under side of a transversely disposed rail 44, which latter is disposed beneath the forward portions of all of the levers 37.

Disposed above the forward portions of levers 37 is a transversely disposed rail 45 that is provided on its under side with a cushioning pad 46, which latter serves as a 90 stop to cushion and limit the upward movement of the forward ends of the damper levers 37.

In the operation of my improved piano action, when a key is struck, its forward 100 end will be depressed and its rear end elevated until pad 32 engages against the head of screw 30. As the key is thus actuated, the laterally projecting finger 41 on the lower end of rod 42 engages against pad 40 105 on the forward end of the corresponding damper lever 37, thereby lifting the forward end of said arm and consequently lifting damper 39 from the corresponding string; and immediately after these operations, the 110 corresponding hammer will strike against the string, which action is brought about by the upward movement of pin 17 and link 15, which latter is directly connected to the lower rear end of hammer arm. 115

In the event that the thumb or finger is immediately removed after striking a key, the parts will immediately return to their normal positions and the vibration of the string that was struck by the hammer will 120 be arrested by the damper 39 as the same again makes contact with said string. But if the key is held in its depressed or shifted position after being struck, the downward pressure on the front portion of said key 125 will compress the felt washers 6 to such a degree as to permit the front portion of the key to move a slight distance downwardly, with the result that the lower end of the hammer 14, which would otherwise bear 130

- on the corresponding string, will elevate slightly or withdraw from said string a sufficient distance to permit the same to vibrate, thereby producing a sustained note.
6. This action is produced as a result of the continued downward pressure upon the key, as said action slightly lowers the parts 15 and 17 and correspondingly lowers the point of pivotal connection between link 15 and
- 10 arm 10, so that said last mentioned arm is swung upon its fulcrum in order to slightly elevate the lower end of the corresponding hammer from the corresponding string.

When the key 2 is depressed the pad 32 strikes the head of the screw 30 and becomes the fulcrum, and while the key is still further depressed the cushion 6 yields, thus tending to shorten the distance between the pivot 14 and the pivot 16, but the link 15 is rigid and this motion will tend to raise the hammer 11 and the second fulcrumming of the key results in the holding of the hammer in raised position after the rebound of the hammer.

25 Ordinarily, the keys swing or fulcrum at the pins 4, but when depressed after being struck so as to slightly elevate the hammer and produce a sustained note as just described said keys fulcrum upon the bearing produced between pad 6 and the head of screw 30.

A soft pedal action is provided whereby to lift the rear ends of the keys 2 and thus shorten the effective strokes of the hammers. Such soft pedal action includes a rod 50 extended down in the usual manner for connection to a pedal and having on its upper end a rail 51 which is provided with a cushion strip, as of felt, 52 normally placed slightly below the rear ends of the keys. Lifting the soft pedal rail 51 brings its cushion 52 into engagement with the keys and these are tilted as above stated to shorten the stroke.

45 Various modifications and changes may be resorted to within the spirit of the invention as claimed.

What is claimed is:

1. A piano action having, in combination, 50 a key, a yielding fulcrum for the key, a hammer, and means mounted upon the key and connected to the hammer, said means providing for the adjustment of the hammer to vary its effective stroke.
- 55 2. A piano action having, in combination, a key, a yielding fulcrum for the key, a fulcrum hammer to strike its respective wire, and adjustable connections between the hammer and the key.
- 60 3. A piano action having, in combination, a key, a yielding fulcrum for the key, a fulcrum hammer to strike its respective wire, and adjustable connections between the hammer and the key, said connections including an adjusting rod mounted in the

key and a connecting link joining said rod and the hammer.

4. A piano action having, in combination, a key, a yielding fulcrum for the key, a fulcrum hammer to strike its respective wire, 70 adjustable connections between the hammer and the key, said connections including an adjusting rod mounted in the key and a connecting link joining said rod and the hammer, and means for locking the adjusting 75 rod in its several positions.

5. A piano action having, in combination, a key, a yielding fulcrum for the key, an adjusting rod mounted through the key, a jack screw, one end of which is supported 80 on the key, said rod being provided with a block engaged by the jack screw whereby upon the rotation of the screw said rod is shifted.

6. A piano action having, in combination, 85 a key, a yielding fulcrum for the key, an adjusting rod mounted through the key, a jack screw, one end of which is supported on the key, said rod being provided with a block engaged by the jack screw whereby 90 upon the rotation of the screw said rod is shifted, and means for retaining the jack screw rotatively in its mounted position.

7. A piano action having, in combination, 95 a key, a yielding fulcrum for the key, an adjusting rod mounted through the key, a jack screw, one end of which is supported on the key, said rod being provided with a block engaged by the jack screw whereby upon the rotation of the screw said rod is shifted, means for retaining the jack screw 100 rotatively in its mounted position, and a locking screw passing through said block and rotative therein and engaging the key whereby to lock the said block on the screw. 105

8. In a piano, the combination with piano strings, of a piano action including hammers, a key for each hammer, a pin adjustably arranged through each key to the rear of its fulcrum and extending downwardly at right angles to the key, and a link connecting the lower end of said pin to one of the hammers. 110

9. In a piano, the combination with piano strings, of a piano action including hammers, a key for each hammer, a pin adjustably arranged through each key to the rear of its fulcrum and extending downwardly at right angles to the key, a link connecting the lower end of said pin to one of 115 the hammers, and means for securing said pin in its adjusted position upon the key. 120

10. In a piano action, a fulcrumed key, a fulcrumed hammer below the key, a vertically adjustable pin seated through the key to the rear of its fulcrum point and extending downwardly at right angles to the key, and a link connecting the lower end of said pin and said hammer. 125

11. In a piano, the combination with pi- 130

- ano strings, of a piano action mounted above the strings and including hammers, a key for each hammer, a yieldable fulcrum for each key, and an actuating connection 5 between each key and its hammer arranged to cause downward swinging of the hammer to strike its string when the key is struck, and subsequent elevation of the hammer from its string upon continued depression of the key so as to cause yielding of said fulcrum.
12. In a piano, the combination with piano strings, of a piano action including hammers, a key for each hammer, a yieldable fulcrum for each key, a stop for limiting the swinging movement of the rear ends of the fulcrumed keys, whereby continued depression of a key will cause yielding of its fulcrum and subsequent fulcruming of the key at said stop, and an actuating connection between each key and its hammer arranged to cause swinging of the hammer to strike its string upon initial fulcruming of the key, and subsequent withdrawal of the hammer from its string upon the subsequent fulcruming of the key.
13. In a piano, the combination with piano strings, of a piano action including hammers, a key for each hammer, a balance rail for said keys, a resilient support between each of said keys and said rail providing yieldable fulcrums for said keys, a stop for limiting swinging movement of the rear ends of the keys, and an actuating connection between each key and its hammer arranged to cause swinging of the hammer to strike its string when the key is struck, and subsequent withdrawal of said hammer from its string upon continued depression of the key.
14. In a piano, the combination with piano strings, of a piano action including hammers, a key for each hammer, a yieldable fulcrum for each key, dampers for said strings, an operating connection between the key and damper for each string arranged to withdraw the damper when a key is struck, and an actuating connection between each key and its hammer arranged to cause the hammer to strike its string when the key is struck, and subsequent withdrawal of said hammer from its string upon continued depression of the key.
15. The combination with a piano action, of hammer actuating keys, a rail carrying cushioning pads beneath the rear portions of said keys, and an adjustable contact device for each key to check the upward swing of the adjacent portion of said key.
16. In a piano, a fulcrumed key, a wire striking hammer connected to and actuated by said key, a rail arranged above the rear end of said key, a screw seated in said rail for limiting the upward movement of the rear end of the key and having a tool receiving slot formed in the upper end of said screw.
17. A piano action including a key fulcrumed between its ends, a hammer arranged below the key behind the fulcrum and above its respective string or wire and an adjustable connection between the key and hammer.
18. A piano action including a key fulcrumed between its ends, a hammer arranged below the key and behind the fulcrum and above its respective string or wire, and adjustable connections carried by the key and joining the hammer thereto.
19. In a piano action, a key and coordinate string, a hammer interposed between the string and the key and adjustably connected to the key, a check rail arranged above the rear end of the key and individual means in the check rail to engage each key in its uppermost position, and a yielding fulcrum for the key.
20. In a piano action, a key and coordinate string, a hammer interposed between the string and the key and adjustably connected to the key, a check rail arranged above the rear end of the key and individual means in the check rail to engage each key in its uppermost position, a yielding fulcrum for the key, and a soft pedal device including a rail for engagement with the rear end of a series of the keys.

In testimony whereof I have signed my name to this specification.

HENRY F. SCHENUIT.
